United States Patent Office

Des. 188,126
Patented June 7, 1960

188,126

SERVING TRAY

George J. Strauss, 6606 10th Ave., Los Angeles, Calif.

Filed Aug. 3, 1959, Ser. No. 57,041

Term of patent 14 years

(Cl. D44—10)

Fig. 1 is a perspective view showing a serving tray embodying my new design;

Fig. 2 is another perspective view of the same;

Fig. 3 is a top plan view of the same, on a reduced scale.

I claim:

The ornamental design for a serving tray, substantially as shown.
